UNITED STATES PATENT OFFICE.

WILLIAM G. EATON, OF HULL, MASSACHUSETTS.

RUBBER HEEL.

Application filed August 23, 1922. Serial No. 583,820.

To all whom it may concern:

Be it known that I, WILLIAM G. EATON, a citizen of the United States, residing in Hull, in the county of Plymouth and State 5 of Massachusetts, have invented an Improvement in Rubber Heels, of which the following description, in connection with the accompanying drawings, is a specification, like characters on the drawings representing like 10 parts.

This invention relates to a rubber heel.

The object of the invention is to provide a rubber heel of novel and improved construction which is attractive in appearance and 15 which is particularly adapted for use by shoe manufacturers for attachment by automatic nailing machines to the heels of new shoes.

To these ends the invention consists in 20 the rubber heel hereinafter described and claimed.

In the drawing illustrating the preferred form of the invention, Figure 1 is a plan of the improved heel; Fig. 2 is a section on line 25 2—2 of Fig. 1; Fig. 3 is a vertical sectional view of the shoe heel to which the improved rubber heel has been attached.

The general practice in the manufacture 30 of rubber heels at the present time contemplates the employment of a series of small flat washers embedded within the body portion of the heels at points substantially midway between the attaching and tread faces thereof and which are adapted to engage the 35 heads of nails driven through preformed holes in the rubber to secure the rubber heels to the shoe heels.

At the present time, rubber heels are being adopted by shoe manufacturers for attachment upon new shoes and the conditions 40 arising from the use of automatic nailing machines present additional difficulties in the practical attachment or nailing of the different types of rubber heels upon the 45 shoes. Among these difficulties the position and angle relative to the preformed nail hole in the rubber heel, and also the washer embedded within the same, at which the individual nails are presented to the rubber 50 heel by the automatic feed of the nailing machine, have been the most troublesome. When nails are thus presented at divergent angles, the points of the nails enter the rubber at places other than the preformed hole 55 in the tread surface thereof, so that in many

instances the nail, when completely driven into place, misses entirely the embedded washer, resulting in the defectively nailed rubber heel. Often times the nail is driven in such manner as to engage the solid portions of the metal washers and is deflected thereby or, on the other hand, it deflects the washer from its normal position. In both events, a defectively nailed heel results. Furthermore, with the type of washers employed at the present time, it is impossible 60 for a shoe manufacturer to determine whether all of the washers are in place within the heel. In the event that one or more of these washers be missing, there is nothing 65 within the heel for the head of the nails to engage, and as a result, the rubber heel is defectively nailed to the shoe heel when any of these washers are absent.

In accordance with the present invention, 70 a rubber heel is provided of a construction such as to insure the proper nailing thereof to a shoe heel even when the automatic nailing machines are employed. Furthermore, 75 the construction of the fastener engaging devices is such as to enable the manufacturer to determine by inspection of the exterior of the heel whether, in fact, the particular fastener engaging devices are in place 80 in the heel.

Referring to the drawing, the illustrated embodiment comprises a body portion 10 having an attaching face 12 and tread face 14. Within the body portion 10 a plurality of fastener engaging devices 16 are embedded preferably of relatively soft metal such as aluminum, and comprising flat washers 18 having the usual holes 20 therein through which the shank of the nails may pass and which are also provided with guide member 22, preferably in the form of a tapered cone, arranged to extend to the tread surface of the heel. During the molding of the heel, the fastener engaging devices are placed or slipped over bosses upon the nailing pins in the mold, the tops of the fastener engaging devices resting upon the bottom plate of the mold.

The presence of the metal cones or tapered guides enhances the appearance of the heel, 105 and enables the manufacturer to determine, by inspection of the surface of the heel, whether in fact, all of the fastener engaging devices are present within the heel before the latter is nailed to a shoe heel. Further- 110

more, the construction and location of the fastener engaging devices within the body of the shoe heel is such that the resiliency of the entire heel is not destroyed because of the solid cushion of rubber below the same.

When the present heels are used in connection with the automatic nailing machine, it will be apparent that diverging nails are guided by the members 22 before they engage the rubber down into a position such that they are caused to pass through the preformed holes in the washers, thus insuring the correct nailing of the heels to the shoes.

In practice it is not absolutely necessary that the conical nail guides 22 taper completely down to the nail washers 18, but if desired the taper may be arranged to terminate at a point as illustrated in Figs. 2 and 3 such that the nails passing from contact with the tapering portion are directed so as to pass through the nail holes in the washers and to, at the same time, provide a flat bearing for the head of the nail.

In the preferred embodiment of the invention, the guide members 22 are preferably formed integrally with the washers 18, and with each construction it will be observed that when the rubber heel is nailed to a shoe heel the nailing pressure is caused by the integral guide members to be exerted upon the heel from bearings toward the tread surface of the heel. This construction is conducive to the production of an improved

and permanent tight joint between the rubber heel and shoe as is fully described and claimed in an application filed by me on even date herewith.

While the present heel is designed particularly for use with the automatic nailing machine, it will be apparent that it may be used to advantage by the ordinary shoe repair man who attaches the heels by hand.

Having thus described the invention, what is claimed is:

1. A rubber heel comprising a body portion having a plurality of conical recesses extending from the tread surface of the heel inwardly toward the attaching face thereof, fastener engaging devices embedded in the body portion of the heel below said recesses, and linings of relatively soft metal for said recesses and extending from substantially the tread surface of the heel toward the fastener engaging devices for directing nails from an automatic nailing machine downwardly to cause their passage through said fastener engaging devices.

2. A rubber heel comprising a body portion provided with a plurality of nail washers embedded therein, and conical nail guides integral therewith extended and tapering from substantially the tread surface of the heel for directing nails from an automatic nailing machine through the nail washers.

In testimony whereof, I have signed my name to this specification.

WILLIAM G. EATON.
